UNITED STATES PATENT OFFICE.

PABLO E. MEDINA, OF MAYAGUEZ, PORTO RICO.

DESIGN FOR A DOLL'S BED.

Application filed June 29, 1926. Serial No. 18,211. Term of patent 7 years.

To all whom it may concern:

Be it known that I, PABLO E. MEDINA, a citizen of the United States of America, residing in Mayaguez, Porto Rico, have invented a new, original, and ornamental Design for Doll's Bed, of which the following is a specification, reference being had to the accompanying drawing, forming part hereof.

The drawing is a perspective view of a doll's bed showing my new design.

I claim:

The ornamental design for a doll's bed as shown.

PABLO E. MEDINA.
